ADJUSTABLE SWITCH-RAIL CLIP.

Application filed September 22, 1921. Serial No. 502,322.

To all whom it may concern:

Be it known that I, ROBERT E. EINSTEIN, a citizen of the United States, residing at St. Louis, Missouri, have invented a certain 5 new and useful Improvement in Adjustable Switch-Rail Clips, of which the following is a full, clear, and exact description, such as will enable others skilled in the art to which it appertains to make and use the same.

10 This invention relates to devices of the kind generally termed "switch rail clips" that are used for adjustably connecting a switch rod to the movable rails of a split switch.

15 The main object of the invention is to provide a switch rail clip that permits of various adjustments between the switch rod and the movable rails of the switch without throwing the switch rod out of longitudinal 20 alignment with the connecting link that joins the switch rod to the switch stand that is used to operate the movable rails of the switch, thereby maintaining the switch rod in such a position that it exerts a direct thrust 25 at all times on the clips at the center line of the clips, and consequently, reducing to a minimum the liability of bending the clips or buckling the switch rod sidewise, as sometimes occurs when a switch rod is subjected to an abnormal strain at a time when 30 it is eccentrically connected to the switch clips or connected to the clips at points located at one side of the center line of the clips.

35 Another object is to provide an adjustable switch rail clip of the type which comprises a horizontally-disposed yoke or U-shaped portion that embraces the switch rod, which is so constructed that the bottom piece of the 40 yoke will not be deflected or bent downwardly when the switch is in service, due to rocking of the movable rails of the switch, thereby eliminating the possibility of the switch rod assuming such a position that it will not 45 properly operate the movable rails of the switch.

50 And still another object is to provide an adjustable switch rail clip of the character above referred to that is simple to adjust; that can be used with the standard switch rod now in general use and substituted for a standard switch rail clip and which overcomes the necessity of moving or cutting the track ties, so as to provide a clearance for

the switch rod in making some adjustments 55 of the clip.

To this end I have devised a switch rail clip that comprises what I will term a stationary part that is rigidly connected to the movable switch rail with which the clip is used, and an adjustable part carried by said stationary part and having provision for enabling a standard switch rod to be connected to the clip at a number of different points in the center line of the clip and without throwing the switch rod out of longitudinal alignment with the link that connects said switch rod to the switch stand. The stationary part of the clip is preferably provided with a horizontally-disposed 70 yoke or substantially U-shaped portion that embraces the switch rod and the adjustable part of the clip is so constructed that it closes the open side of said yoke and prevents the top and bottom pieces of the yoke 75 from spreading under certain conditions, the adjustable part of the clip herein shown consisting of a horizontally-disposed yoke that embraces the yoke-shaped portion of the stationary part of the clip and which is mounted on said stationary part in such a manner that it is held against movement longitudinally of the switch rod, but is capable of being adjusted transversely of the switch rod. The connection between the switch rod and the clip is made by a bolt or other suitable fastening device that passes through the switch rod and the adjustable 80 part of the clip, and said adjustable part is provided with a number of holes for said 85 bolt or fastening device arranged in such a manner that shifting said adjustable part transversely of the stationary part of the clip brings into service a different bolt hole whose position is such that a change will be 90 effected in the point of connection between the switch rod and the clip when the bolt or fastening device is inserted in said hole. In other words, the adjustable part of the clip is provided with a number of bolt holes 95 located different distances from the rail to which the clip is connected, and said adjustable part is mounted on the stationary part of the clip in such a manner that it can be shifted relatively to same so as to bring any one of said holes into longitudinal alignment with the center line of the switch rod and the center line of the stationary part of

100 105

the clip so as to receive the bolt or other device that is used for connecting the switch rod to the clip.

Figure 1 of the drawings is a top plan view of a railway switch equipped with adjustable clips constructed in accordance with my invention.

Figure 2 is a transverse sectional view of said switch.

10 Figure 3 is a perspective view, illustrating the stationary part and the adjustable part of the clip separated; and

15 Figures 4 and 5 are top plan views of the clip, showing the adjustable part of the clip arranged in different positions.

Referring to the drawings, A designates the movable rails of a split switch, B designates a switch rod that is connected to said movable rails so as to change the position of 20 same and C designates the link that is used for connecting the switch rod B to the switch stand (not shown) that is used for operating the switch.

25 My invention consists in an adjustable clip of novel construction for connecting the switch rod B to the movable rails A of the switch. Said clip is composed of two parts, namely, a stationary part X that is rigidly connected to the movable rail of the 30 switch with which the clip co-operates, and an adjustable part Y mounted on the stationary part X of the clip and provided with means that enables the switch rod B to be connected to the clip at a number of different points in longitudinal alignment with the center line of the clip. In the form of 35 my invention herein illustrated the stationary part X of the clip comprises a horizontally-disposed yoke or substantially U-shaped portion 1 integrally connected to a bracket 2 having a vertical portion 3 through which bolts or other suitable fastening devices 4 pass so as to rigidly connect said bracket to one of the movable rails A 40 of the switch. The adjustable part Y of the clip consists of a horizontally-disposed, yoke-shaped member that is adapted to be slipped transversely over the yoke-shaped portion 1 of the stationary part X, the top 45 and bottom pieces of the yoke-shaped portion 1 of the stationary part having transversely-disposed grooves formed in same so as to form shoulders 5 on the stationary part X that take up the longitudinal thrusts to 50 which the adjustable part Y is subjected from the switch rod B.

55 The switch rod B is embraced by the yoke-shaped portion 1 of the stationary part X of the clip and is adjustably connected to said stationary part by means of the adjustable part Y of the clip, and a bolt or fastening device 6 that passes through said switch rod and through one pair of a series of aligned holes in the top and bottom pieces of the 60 adjustable part Y of the clip, the yoke-

shaped portion 1 of the stationary part of the clip being provided with elongated slots or openings 7 through which the bolt 6 passes. Accordingly, the bolt 6 serves to 70 connect the switch rod to the adjustable part Y of the clip and it also prevents said adjustable part from moving transversely with relation to the yoke-shaped portion 1 of the stationary part of the clip. The slots 7 in said yoke-shaped portion are of sufficient length to permit the adjustable element 75 Y of the clip to be arranged in various positions, as hereinafter described, without causing the bolt 6 to bear against the ends of said slots, as I prefer to transmit the thrust 80 from the switch rod to the stationary part of the clip through the adjustable part Y and the shoulders 5 on the stationary part against which said adjustable part Y bears.

85 The adjustable part Y of the clip may be provided with any desired number of holes arranged in any preferred manner to receive the bolt or other device 6 that is used for connecting the switch rod to the clip, but I prefer to form two or more holes in each of the top and bottom pieces of the adjustable part Y on a line that extends at an angle to the rail to which the clip is connected so that each pair of vertically aligned holes in the part Y will be located a different distance from the rail to which the clip is connected. In the form of my invention herein illustrated the adjustable part Y of the clip is provided with three sets of vertically aligned holes 8, 8^a and 8^b, as shown in Figure 3, the holes 8 being located close to the rail to which the clip is connected, the holes 8^a a slightly greater distance from the rail and the holes 8^b a still greater distance from the rail, as shown more clearly in Figure 1. Assuming that the bolt 6 is arranged in the vertically aligned holes 8^b in the adjustable part Y of the clip, as shown in Figure 4, and that it is desired to move the rail A to which the clip is connected closer to the main rail of the track with which said movable rail co-operates, it is only necessary to remove the bolt 6, shift the adjustable part Y of the clip transversely of the stationary part X so as to bring the bolt holes 8^a in the part Y into alignment with the elongated slots 7 in the stationary part of the clip and then insert the bolt 6 in the holes 8^a and in the hole of the switch rod B, as shown in Figure 5, thus causing the point of connection between the clip and the switch rod to be changed without throwing the switch rod to one side or the other of the center line of the clip and without throwing the switch rod out of longitudinal alignment with the link that connects said rod to the switch stand. Similarly the holes 8 in the adjustable part of the clip can be used for effecting another adjustment between the clip and the switch rod. The

holes 8, 8^a and 8^b in the top and bottom pieces of the adjustable part Y are arranged closer to one of the longitudinal edges of said part than to the other longitudinal edge of said part. This feature of my invention is shown more clearly in Figures 4 and 5, wherein it will be noted that the center holes 8^a are arranged closer to the outer edge of the part Y (the top edge looking at Figures 4 and 5) than to the inner edge of said part. Likewise, the distance between the outer edge of the part Y and the centers of the holes 8^b is less than the distance between the centers of the holes 8 and the inner edge of the part Y. The purpose of arranging the holes in the part Y in the manner above described is to enable said part Y to be reversed so as to obtain three additional adjustments, for when said part Y is reversed the holes 8, 8^a and 8^b will be arranged closer to the rail than when said part Y is in the position shown in Figures 4 and 5. Consequently, a clip whose adjustable part is provided with three sets of holes arranged on a line that extends at an angle to the rail with which the clip co-operates and positioned closer to one of the longitudinal edges of said part than to its other longitudinal edge, is capable of six separate adjustments to change the point of connection between the clip and the switch rod. In each adjustment of the clip the bolt 6 that connects the switch rod to the clip occupies the same position, namely, it remains in the center line of the clip and in the center line of the switch rod. Consequently, with an adjustable switch clip of the construction above described there is no liability of bending the clip or buckling the switch rod, as so often occurs when a switch rod is subjected to an abnormal strain at a time when it is eccentrically connected to the switch clips or connected to the switch clips at points to one side of the center line of the clips. In other words, my clip is distinguished from adjustable switch clips of this general type that have heretofore been in use, in that the bolt or fastening device that is used for connecting the switch rod to the clip is always located in the center line of the clip, thus insuring that the switch rod will exert a direct thrust on the clip and also insuring that the switch rod will remain in longitudinal alignment with the link that joins said switch rod to the switch stand. Moreover, a switch clip of the construction above described is much stronger than prior switch clips of the type that comprise a horizontally-disposed yoke which embraces the switch rod, owing to the fact that the adjustable part Y of my improved clip embraces the top and bottom pieces of the yoke-shaped portion of the stationary part X of the clip and prevents the bottom piece of said yoke-shaped portion from being deflected or bent downwardly by a vertical rocking movement of the rail to which the clip is connected, and thus interfering with the proper working of the movable rails of the switch under traffic. As the switch rod always remains in the same position, irrespective of the position of the adjustable part Y of the clip, it is not necessary to move or cut away the track ties to provide a clearance for the switch rod in certain adjustments of the clip, as is necessary with some kinds of adjustable switch clips that have heretofore been devised. Moreover, my switch clip is of such design that it is not difficult for a track laborer to understand how to adjust same; it can be used with a standard switch rod and it can be interchanged with the type of switch clip now in general use.

Having thus described my invention, what I claim as new and desire to secure by Letters Patent is:

1. An adjustable switch clip, comprising a stationary part adapted to be connected to a switch rail and provided with an elongated hole, an adjustable part on said stationary part provided with a plurality of holes located different distances from the switch rail and adapted to be moved transversely of said stationary part so as to bring a selected hole in said adjustable part into longitudinal alignment with the elongated hole in said stationary part, a switch rod, and a removable fastening device passing through said selected hole and elongated hole for securing the switch rod to said adjustable part.
2. An adjustable switch clip, comprising a stationary part that is adapted to be connected to a switch rail and provided with an elongated hole arranged in the center line of said part for receiving a fastening device secured to a switch rod, and an adjustable element on said part provided with a plurality of holes located different distances from the rail to which the clip is connected and adapted to be moved transversely of said stationary part so as to bring a selected hole in said element into alignment with said elongated slot so as to receive the fastening device on the switch rod.
3. An adjustable switch clip, comprising a stationary part that is adapted to be connected to a movable switch rail, and a transversely adjustable element on said part having provision for enabling a switch rod to be connected to same at a number of points, said element being so constructed that it can be reversed end for end for the purpose described.
4. An adjustable switch clip, comprising a stationary part adapted to be connected to a movable switch rail and provided with a yoke-shaped portion that is adapted to loosely embrace a switch rod provided with

a bolt, a yoke-shaped element embracing the yoke-shaped portion of said stationary part and mounted on same in such a manner that it can be adjusted transversely of said yoke-shaped portion, and a plurality of holes in said yoke-shaped element located different distances from the switch rail to which the clip is connected for receiving the bolt in the switch rod.

10. 5. An adjustable switch clip, comprising a stationary element adapted to be connected to a switch rail and provided with a horizontally-disposed, yoke-shaped portion

for receiving a switch rod, said yoke-shaped portion having transversely-disposed grooves in the top and bottom pieces of same, a yoke-shaped element embracing the yoke-shaped portion of said stationary part and slidably mounted in grooves in same, and means for connecting the switch rod to said yoke-shaped element and for preventing said yoke-shaped element from moving with relation to the part which it embraces.

ROBERT E. EINSTEIN.
